UNITED STATES PATENT OFFICE.

THOMAS B. ATTERBURY AND JAMES S. ATTERBURY, OF PITTSBURG, PA.

DESIGN FOR LAMP-FOOT.

Specification forming part of Design No. 6,948, dated October 7, 1873; application filed September 19, 1873.
[Term of Patent 7 years.]

To all whom it may concern:

Be it known that we, THOMAS B. ATTERBURY and JAMES S. ATTERBURY, of Pittsburgh, in the county of Allegheny, and State of Pennsylvania, have invented a new and original Design for a Lamp-Foot; and we do hereby declare the following to be a full, clear, and exact description thereof, reference being had to the accompanying drawing making part of this specification, in which—

Figure 1 is a side view of lamp-foot, showing our new design. Fig. 2 is a horizontal section of the same in the line *x x* of Fig. 1, looking downward.

In a side view, the base portion *A* of the foot shows vertical sides *a a*, and horizontal top and bottom surfaces *b b*, the latter beveled off at the corners *c c*. Between the horizontal surfaces depressed panels *d d* are seen, the panels being bounded by beveled surfaces *e e*, the vertical beveled surfaces terminating in flat surfaces *f f*, and the horizontal beveled surfaces terminating in flat surfaces *g g*. All of the flat projecting surfaces described are flush with one another. Mounted upon the base portion *A* is a short column *B* of approximately pyramidal form, the profile of this column presenting curved concave lines *h h*, which decrease in extent of curvature from their bases to their upper terminuses, as shown. This column presents panels *i i*, which are inclosed at their

lower end by a flat-sided surface, *j*, and at sides and top by beveled surfaces *k k'*, which terminate in flat surfaces *l l'*, the surfaces *l l'* being surmounted by a half-round bead, *m*, as shown. All of the flat surfaces of this column are flush with one another. The profile of the base portion *A* of the foot is an octagon with the angles or corners cut off flat; its profile may, however, be polygonal, hexagonal, or any other analogous angular shape. The profile of the column of the foot is a hexagon with its angles or corners cut off. Its profile, like the base portion, may also be of any analogous angular shape.

What we claim, is—

The design for the foot of a lamp, consisting of the base *A* with its panels *d*, bounded with beveled surfaces *e*, which terminate in flat surfaces *f g*, and the column *B* with its panels *i* bounded with beveled surfaces *k k'*, which terminate in flat surfaces *l l' j*, and finished at top with a bead, *m*, the profile of the column and base in horizontal section being polygonal, and in front elevation curved as at *h*, and vertical as at *a*, as described and shown.

THOS. B. ATTERBURY.
JAMES S. ATTERBURY.
